UNITED STATES PATENT OFFICE.

WILLIAM M. SMELO, OF PHILADELPHIA, PENNSYLVANIA.

WIRE-WORKING MACHINE.

1,294,314.

Specification of Letters Patent. Patented Feb. 11, 1919.

Application filed February 3, 1917. Serial No. 146,449.

To all whom it may concern:

Be it known that I, WILLIAM M. SMELO, a citizen of the United States, residing in Philadelphia, Pennsylvania, have invented 5 certain Improvements in Wire-Working Machines, of which the following is a specification.

My invention relates to wire-working or wire-twisting machines; and the object of 10 my invention is to form a reinforcing fabric structure made of twisted "warp" threads of wire, which tie together, in spaced relation, reinforcing bars of light or heavy construction as the case may be. For this purpose I 15 provide means for feeding rods to suitable positions with respect to a plurality of rotating members, each of which carries a wire reel so that strands of wire therefrom may be wrapped around the bars as they are disposed at regular intervals; the said wire 20 strands being subsequently twisted between such bars so that the latter can be held in definitely spaced relation.

These and other features of my invention 25 are more fully described hereinafter, reference being had to the accompanying drawings, in which:

Figure 1. is a diagrammatic view, showing a front elevation of a machine made in 30 accordance with my invention and designed for twisting strands of wire together and around reinforcing bars.

Fig. 2. is a diagrammatic plan view of the same.

Fig. 3. is an elevation on an enlarged scale of a portion of the structure shown in Fig. 1.

Fig. 4. is a sectional view on the line IV—IV, Fig. 3, and

Figs. 5, 6 and 7. are views illustrating 40 details of my invention.

In the drawings, 1 represents a suitable table to which bars 2 may be fed by chains 3, which may have means in the form of projections or arms disposed at relatively fixed 45 points (not shown) to engage the bars and feed them in fixed relation to each other. Above and below the table are frames 4 and 5, respectively, in which are mounted wire-carrying reels 6 and 7 so disposed in suitable 50 rotatable carriers 8 and 9, in which they are also rotatable on their own axes, as to be movable as a whole around the axis of the carriers around which the strands of wire are twisted.

As the axis of rotation of the reel-carriers 55 must be open for the passage of the bars at

the desired intervals for engagement by the twisted wires, I provide a special form of hub with driving gearing therefor whereby said carriers with their rotatably mounted 60 reels may be caused to rotate around said open axis. To this end, the opposite walls of the frames 4 and 5 may be provided with a plurality of sets of rollers 10 and 11 disposed in curved relation with respect to sets 65 of semiamnular hub flanges 12 and 13 mounted on or carried by said reel-carriers; one of said sets of hub flanges being toothed for engagement with driven gears 14 whereby said reel carriers may be rotated with respect to their axis "A" and deliver wire 70 strands from the reels 6 and 7 to be twisted together and around the bars 2 fed to the same.

In order that the carriers may be driven 75 simultaneously, I provide paralleling shafts 15 and 16, each provided with bevel gears 17 and 18, adapted to mesh with bevel gears 19 and 20 which may be carried by stud shafts 21 and 22 journaled in the frames 4 and 5. 80 The shafts 21 and 22 may also carry gears 23 and 24, for engagement with gears 25 mounted on stub shafts 26, which latter shafts may carry the gears 14 in engagement with the toothed portions 13 of the hub 85 flanges of the carriers 8 and 9. It can readily be seen therefore that when this gearing is in action, the reel carriers 8 and 9 will be moved around the open axis "A" through which the rods pass; twisting the wire 90 strands from the respective reels together and around the bars 2.

The carriers 8 and 9 may be provided with laterally projecting stems 6^a and 7^a upon which the wire reels may be journaled. 95 From the reels, the wire strands may pass over small grooved rollers 27, 28 and 29, to the point of twisting, around the bars and around themselves, as shown in Fig. 4.

The shafts 15 and 16 may be driven from a main driving shaft 31 through the interposition of gearing indicated at 32, 33 and 34; the main driving shaft being provided with a suitable clutch 35 so that while said shaft may be in action at all times, the 100 shafts 15 and 16 may be thrown into and out of operation as desired.

In practice, the ends of the wires may be caught around a bar, (first entered), and then secured. The rotation of the carriers 110 is then started, and as the chains 3 feed the bars in regular order consecutively, the wire

strands will be simultaneously twisted around the same to connect the bars, and then twisted together to hold the bars in spaced relation.

5 While I have shown in Figs. 3 and 4, an arrangement of gearing which involves the use of pinions 25 mounted on stub shafts 26 which also carry the gears 14 meshing with the toothed hub sections 13, it will be
10 understood that I may, if desired, gear the wheels 23 and 24 directly with the gears 14 and avoid the necessity of employing the extra gearing disclosed. Such arrangement, of course, merely constitutes a change in the
15 mechanism for driving the reel carriers and is entirely within the scope of my invention.

I claim:

1. The combination, in a wire weaving
20 machine, of a pair of wire reels, a vertically disposed carrier for each reel and in which the latter is rotatably mounted, a split gear in two sections; each carrier having a section
25 of said gear; said gear sections being rotatable around a common axis and the reels being rotatable around axes supported by the carriers parallel to the axis of rotation of the split gear, independently arranged sets of gears for simultaneously driving each section of the split gear, a pair of shafts for actuating said gearing, and means
30 for simultaneously driving said shafts whereby the sections of said split gear and the carriers supporting the same may
35 change position with reference to the frame of the machine without changing the relative position of the carriers with respect to each other.

2. The combination, in a wire weaving machine, of a frame, a pair of independent 40 movable carriers vertically disposed and rotatable in unison around a common axis, a wire reel mounted in each carrier and rotatable on an axis parallel to the axis of rotation of the carriers, independent gear sections mounted on each carrier in definite spaced relation with respect to each other, a flange mounted on each carrier in concentric relation to the gear sections, gearing meshing with said split gear sections for 50 rotating the carriers; the latter maintaining their relative position with respect to each other, and rollers forming a bearing support for said split gear sections and the concentric flanges and around which they 55 may turn.

3. The combination of a frame, a plurality of independent vertically disposed reel carriers, reels rotatably mounted in said carriers, a plurality of rollers forming a bearing upon which said carriers may rotate, gear sections mounted on said carriers and disposed in spaced relation with respect to each other, flanges disposed on the carriers in concentric relation to said gear sections; said gear sections and flanges being journaled upon and adapted to rotate with respect to the several rollers, and gearing meshing with said gear sections for effecting simultaneous movement of the carriers upon which they are mounted whereby their relation with respect to each other is unaltered.

In witness whereof I affix my signature.

WILLIAM M. SMELO.
